UNITED STATES PATENT OFFICE.

ROBERT L. STILLSON, OF NEW YORK, N. Y., ASSIGNOR TO THE BARNHART BROTHERS & SPINDLER, OF CHICAGO, ILLINOIS.

DESIGN FOR A FONT OF PRINTING-TYPE.

SPECIFICATION forming part of Design No. 32,116, dated January 16, 1900.

Application filed December 20, 1899. Serial No. 741,068. Term of patent 3½ years.

To all whom it may concern:

Be it known that I, ROBERT L. STILLSON, a citizen of the United States, residing at New York, State of New York, have invented and produced a new and original Design for a Font of Printing-Type, of which the following is a specification, reference being had to the accompanying facsimile of the same, forming a part thereof.

This design comprises capitals, figures, and dollar-mark, character &, points, and one ornament. Its general characteristics are that the characters are quite extended and marked by a strong contrast between light and heavy lines. All straight lines have minute or relatively small serifs. Incomplete oval curves, as of C, G, J and figures 3, 5, 6, and 9, are very heavily swell-shaded, the shade merging in a fine line terminally finished with a serif. Letters L and R have the characteristic tail-stroke extended and tapering very gradually through the greater part of its length and finishing to a fine terminal quite abruptly in a culminating curved portion at the right. O and Q are exteriorly circular, being swell or crescent shaded on opposite sides of an axis inclined rearward—that is, to the left—leaving the central space prominently oval and inclined to the left. The upper small oval element of figure 9 is given an oblique rearward incline in appearance by a similar expedient, consisting of forming a crescent swell shade on the lower left-hand side. The characteristic center stroke of E and the corresponding stroke of F and cross-stroke of H are prominently above the middle of the letters, respectively. The upper element of figures 3, 5, and 8, are relatively quite small, and the upper hook curve of figure 2 is similarly restricted to a corresponding appearance. Letter S has the circumflex shade connecting the two hooks extending nearly vertically and occupying a very large portion of the letter, the hooks being relatively small and extending laterally beyond the convex curves of the shade.

The character & has the lower oval crescent shaded, the swell or crescent of the shade comprising about three-quarters of the entire circumference and being disposed obliquely, the climax of the shade being at the lower left-hand side, analogous to capital Q. The upper “snail” element comprises a crescent shade at the left hand, broken at the upper point and merging by light, but not hair, 50 line in a small heavy crescent, having its climax at the lower right hand. The characteristic of this character is the circumflex, heavily shaded at both ends to an abrupt or slightly concave termination, said character 55 being located crossing the light-line right-hand portion of the lower oval, so as to present the similar abrupt end facing downward facing on the line, and the larger facing upward to the right. 60

The interrogation-point has the finials substantially identical with the letter S and the circumflex swell shade distinctly heavier at the lower than at the upper part. 65

The dollar-mark has the finials heavily 70 shaded and terminating abruptly, the lower left hand being the larger and its abrupt termination being the larger, the upper and smaller finial terminating at an abrupt line inclined about forty-five degrees to the right. 75

The ornament comprises a pair of conventional eagle-wings symmetrically disposed at opposite sides of a conventional miniature torch. 80

I claim—

The design for the font of printing-type herein shown and described.

In testimony whereof I have hereunto set my hand, at New York, N. Y., this 29th day of November, 1899.

ROBERT L. STILLSON.

In presence of—

AUGUSTA ROHEBERG,
GEO. E. MINER.
